ARC FURNACE ELECTRODE CONTROL APPARATUS

James Wright Moore, Pittsburgh, Pa., assignor to McGraw-Edison Company, Milwaukee, Wis., a corporation of Delaware

Filed Sept. 6, 1962, Ser. No. 221,762
9 Claims. (Cl. 314—61)

This invention relates to arc furnaces and more particularly to apparatus controlling the position of arc furnace electrodes.

It is common practice in the production of high-grade steel to utilize polyphase electric arc furnaces having a plurality of electrodes and electrode positioning means associated with each of the electrodes. Current flows in such furnaces from the electrodes to the grounded furnace charge. That portion of the current path between the electrodes and the furnace charge comprises an arc, which provides the heat necessary for furnace operation. The electrode positioning means is adapted to position each of the electrodes in accordance with the length of its respective arc as indicated by the arc current and the arc voltage so that when the arc current rises, indicating that the arc is too short, the electrode is raised and when the arc voltage rises, indicating that the arc is too long, the electrode is lowered.

It is an object of the invention to provide new and improved fluid control means for positioning the electrodes in an electric arc furnace.

Another object of the invention is to provide fluid control means for positioning the electrodes of an electric arc furnace wherein no positive drive means is required during an electrode lowering operation.

A further object of the invention is to provide two-speed electrode positioning means wherein the speed of electrode travel may be rapidly and conveniently changed therebetween.

These and other objects and advantages of the invention will become more apparent from the detailed description thereof taken with the accompanying drawing which schematically illustrates the electrode controlled mechanism according to the instant invention.

Referring now to the drawing in greater detail, an electric arc furnace 1 is shown to include a shell 2 containing a bath of molten furnace charge or melt 3 and three movable electrodes 4, 5 and 6 positioned above the melt 3. The electrodes 4, 5 and 6 are connected to three phase supply conductors 7, 8 and 9, respectively, which are, in turn, connected to a suitable source of three phase power (not shown). A fluid motor 10 is mechanically connected to each of the electrodes 4, 5 and 6 by an electrode positioning arm 12 so that said electrodes may be raised and lowered in accordance with furnace conditions. Since identical operating mechanisms are provided for controlling the positioning of each of the electrodes 4, 5 and 6, only one of them is illustrated for the sake of brevity.

The hydraulic motor 10 includes a cylinder 13 and a piston 14 coupled to the arm 12 and is actuated by the hydraulic control mechanism according to the instant invention which is shown to include an electrode condition sensing assembly 15, a hydraulic drive assembly 16 and a hydraulic control circuit 18.

The sensing assembly 15 includes a force balance device 19 coupled to the phase conductor 7 for sensing the voltage and current conditions therein and for providing a first output signal when said voltage and current conditions indicate the necessity of an electrode raising operation and a second electrical signal when said conditions indicate the necessity for an electrode lowering operation. The hydraulic control circuit 18 is coupled to the force balance device 19 and is operable upon the receipt of the

2

first signal to couple the pressure side of the hydraulic motor 10 to the hydraulic drive mechanism 16. The hydraulic control circuit 18 is also operative upon the receipt of the second signal from the force balance mechanism 19 to vent the pressure side of the hydraulic motor 10 to a sump 20.

The force balance device 19 is of a conventional type and includes a pair of electromagnetic coils 22 and 24 having armatures 25 and 26, respectively, which are coupled to the opposite ends of a balance beam 28 which is pivotally mounted at its center on a fulcrum 30. Beam 28 is composed of an electrical conductive material and carries a first electrical contact 31 adjacent the end coupled to plunger 25 and a second electrical contact 33 carried by the end connected to plunger 26. A first stationary contact 34 is disposed in spaced relation below the movable contact 31 and a second stationary contact 36 is disposed in spaced relation below the movable contact 33.

A pair of springs 38 and 39 engage the beam 28 in the opposite sides of the fulcrum 30 and are of equal strength so as to hold the beam 28 in a balanced position with the contacts 31 and 33 out of engagement with the contacts 34 and 36 respectively when the coils 22 and 24 are de-energized. The beam 28 is connected by a conductor 37 to a ground bus 40.

Electrode current is sensed by means of a current transformer 41 whose secondary is inductively coupled to phase conductor 7 and a voltage proportional to this current is derived by means of an adjustable resistor 42 shunting the secondary of current transformer 41. Coil 22 is connected across resistor 42 so that the voltage applied to the former will be proportional to the current flowing in phase conductor 7. A voltage proportional to the voltage across the electrode 4 is applied to coil 24 by means of an adjustable resistor 44. Conductors 45 and 46 connect resistor 44 in series with coil 24 and the combination in parallel with the electrode 4. By the suitable adjustment of resistors 42 and 44, the voltage across the coil 22 and the coil 24 can be made equal when the predetermined desired voltage and current conditions exist in electrode 4, whereby the beam 28 will remain in a neutral position with the contacts 31 and 33 out of engagement with the contacts 34 and 36.

The hydraulic driving mechanism 16 includes a pump 48 driven by a motor 50 and having an inlet connected by a conduit 51 to the sump 20 and an outlet connected by a first conduit 52 to the pressure side of the piston 14 and by a second conduit 53 to the hydraulic control circuit 18. A filter 54 and a shut-off valve 55 are disposed in conduit 51. In addition, a check valve 57 and a pressure relief valve 58 are disposed in conduit 52 adjacent the outlet side of pump 48 while a shut-off valve 60 is disposed in said conduit adjacent the cylinder 13. A bypass conduit 62 and a regulating valve 63 connect the output of pump 48 to the conduit 51 so that fine adjustments may be made in the fluid delivery rate to the piston 14.

Motor 50 is of the two speed, three phase AC type and is schematically illustrated to include a first set of input terminals 62 and a second set of input terminals 64 which are selectively engageable by a selector switch 65. When the selector switch engages the first terminals 64, the motor 50 will run at approximately twice the speed upon being energized as it will when the switch 65 engages the second terminals 62. As a result of this two-speed operation of motor 50 and accordingly of the pump 48, the output of the pump 48, and hence the upward velocity of the piston 14, may be correspondingly doubled.

The selector switch 65 is connectable to a three phase alternating current supply system 67 by a solenoid switch 68 operable to close contacts 69. One side of the coil 70 of the solenoid switch 68 is connected to a supply

bus 71 while its other end is connected by conductor 72 to the first stationary contact 34 of the force balance device 19. It will be recalled that the conductive beam 28 of the device 19 is connected to the ground bus 40 by a conductor 37.

The hydraulic control circuit 18 includes three pressure responsive control valves 80, 81 and 82 and each is provided with a solenoid operated pilot valve 85, 86 and 87, respectively. Control valve 80 is disposed in conduit 53 and valve 81 is disposed in a conduit 88 which is connected at one end to the conduit 53 at its downstream side to the sump 20. It can also be seen that valve 82 is connected by conduit 89 in parallel with valve 81.

Each of the valves 80, 81 and 82 are identical and each respectively includes a valve element 90, 91 and 92 which is biased by a spring 100, 101, and 102 towards a seat 110, 111, and 112. Each of the valves 80, 81 and 82 also respectively includes a diaphragm 120, 121, and 122 which is connected to its associated valve elements 90, 91 and 92 by stems 130, 131, and 132, respectively.

Each of the solenoid operated pilot valves 85, 86 and 87, respectively, includes solenoids 95, 96 and 97 which are connected by stems 105, 106, and 107 to valve elements 115, 116, 117, respectively. A spring 123 biases valve element 115 of valve 85 away from its seat 136 while springs 136 and 137, respectively, bias elements 116 and 117 toward their seats 136 and 137.

The solenoid coil 145 of valve 85 is connected by conductor 138 and manually operable switch 139 between the supply bus 71 and the ground bus 40. Coil 146 of valve 86 is connected by conductor 140 to the supply bus 70 and by conductor 141 to the stationary contact 36 of balance device 19 through a pressure switch 142. A conductor 143 and a switch 144 connect the solenoid coil 147 of valve 87 in parallel with the coil 146 of valve 86.

Pressure switch 142 includes diaphragm 150 connected by a conduit 151 to the pressure side of piston 14 and is operative when said pressure is at a predetermined minimum value to hold contacts 152 in a closed position against the action of a spring 153 to thereby maintain the integrity of conductor 141.

A pilot supply conduit 155 is connected to conduit 53 through a pressure reducing restriction 156. Conduits 157, 158 and 159 connect the pressure sides of diaphragms 120, 121 and 122, respectively, to the pilot supply conduit 155 through their associated pilot valves.

Operation of the electrode control system will now be discussed. Assume that normal operation of the piston 14 is desired. In this event, the selector switch 65 is positioned on the first terminals 62 and the switch 144 is open. In addition, the emergency shut-off switch 139 is open to maintain solenoid 145 de-energized so that spring 125 holds element 115 in open position whereby pilot fluid is provided through conduit 157 to the pressure side of diaphragm 120 thereby holding element 90 in open position. Assume further that the electrodes 4, 5 and 6 have been energized and initially lowered into proximity with the furnace charge 3 so that an arc is struck between each and the grounded charge.

If the voltage and current conditions in the electrode 4 are within the desired limits, the voltage across coils 22 and 24 will be substantially balanced so that they will exert equal downward pulls on their respective plungers 25 and 26 whereby the beam 28 will remain in a substantially horizontal position and the movable contacts 31 and 33 will be out of engagement with the stationary contacts 34 and 36, respectively. Under this condition of operation, solenoid 63 will remain open circuited so that contacts 69 will be open and motor 50 de-energized. As a result, the pump 48 will be at rest and no fluid will be delivered to the pressure side of piston 14 so that there will be no upward movement of the electrode 4. Also, downward movement of the piston 14, due to leak-

age through the pump 48, is prevented by the check valve 57.

In addition, because contacts 33 and 36 are out of engagement, solenoid 95 will also be de-energized so that valve 85 will be closed and no pilot fluid will be provided to diaphragm 121 whereby valve 81 will also be closed to prevent the discharge of fluid from the pressure side of piston 14 through conduits 88 or 89. As a result, the piston 4 will be at rest.

Should the current in electrode 4 increase, indicating that the electrode is too low, the voltage across coil 22 will correspondingly increase. An increase in arc current also causes a decrease in arc voltage so that the voltage across coil 24 will decrease. As a result, the force of coil 22 acting on its plunger 25 will overcome the force of coil 24 and on plunger 26 so that beam 28 will pivot counterclockwise to bring contact 31 into engagement with the fixed contact 34 and thereby complete an energizing circuit through the coil 70 of solenoid 63 traced from supply bus 71 to ground bus 40 through conductors 72 and 37 and the conductive beam 28.

The energizing of coil 70 closes contacts 69 to energize motor 50 which, in turn, drives the pump 48 and provides hydraulic pressure to piston 14 which begins moving upwardly to raise the electrode 4.

As electrode 4 rises, the arc current will decrease and the arc voltage will increase until the downward forces of coils 22 and 24 will again be in balance to separate contacts 31 and 34 and de-energize solenoid 63. This opens circuits the motor 50 whereupon the electrode 4 will again come to rest.

If, on the other hand, the arc between the electrode 4 and the furnace charge 3 becomes too long so that the arc voltage increases and the arc current decreases to values which exceed the desired limits, the voltage applied across coil 24 will exceed that applied across coil 22. As a result, the downward force exerted by coil 24 and its plunger 26 will exceed that exerted by coil 22 on plunger 25 so that beam 28 will pivot clockwise to bring contact 33 into engagement with stationary contact 36. This completes an energizing circuit to the coil 146 of solenoid 96 from supply bus 71 through ground bus 40 traced through conductors 140 and 141, pressure switch 142, conductive beam 123 and the conductor 37. As a result, valve 86 will open to provide pilot pressure to diaphragm 121 whereupon valve 81 will open. This completes a discharge path from the piston 14 to the sump 20 through the conduits 53 and 88. As a result, the electrode 4 will begin lowering toward the charge 3. A fine adjustment of the rate of this lowering operation may be made by the setting of a regulating valve 83 in the conduit 88.

As the electrode 4 approaches the charge 3 the arc will shorten to increase the arc current and decrease the arc voltage until a balance condition again exists between the coils 22 and 24. Upon the latter event, the balance beam 28 will resume a horizontal position moving contacts 33 out of engagement with the contacts 36. The solenoid 96 is thereby de-energized so that pilot valve 86 closes to disconnect the diaphragm 121 from the pilot supply conduit 155. As a result, leakage to the sump 20 through a restricted conduit 151 allows spring 101 to overcome the diaphragm 121 and move element 91 onto its seat 111 and thereby interrupt the further discharge of the rate of this lowering operation may be made by the setting of a regulating valve 83 in the conduit 88.

In the event that it is desired to run the electrode 4 at twice normal speed, the switch 65 is placed on the second set of motor contacts 64 so that the motor 50 will drive the pump 48 at twice normal speed. As a result, the pump 48 will supply fluid to the cylinder 14 at twice the previous rate whereupon the electrode 4 will be raised at twice normal speed upon closing of contacts 31 and 34.

In addition, in order for the electrode 4 to lower at twice rated speed, switch 144 in conductor 143 is also

closed, placing solenoid 97 in parallel with solenoid 96. As a result, the closing of contacts 33 and 36 will energize solenoid 97 as well as solenoid 96 so that both valves 81 and 82 will be open to provide parallel discharge paths through conduits 88 and 89. This allows the piston 14 to move downwardly at twice normal speed.

Pressure valve 142 is a fail-safe device which prevents the energization of solenoids 96 and 97 and the consequent downward movement of electrode 4 in the event that the pressure beneath the piston 14 falls below a minimum desired value.

If it is desired to prevent the automatic downward movement of electrode 4, switch 139 in conductor 138 is closed to energize solenoid 95. Upon this event, valve element 115 closes to remove pilot pressure from the diaphragm 120 whereupon valve 80 closes to prevent the flow of discharge fluid between conduit 53 and conduits 88 or 89.

A pressure relief bypass valve 161 is connected in parallel with a filter 162 connected in the leakage conduit 88 so that in the event filter 162 becomes clogged, the lowering of the electrode 4 will not be prevented.

While only a single embodiment has been shown and described, it is not intended that the invention be limited thereto but only by the scope of the appended claims.

I claim:

1. Means for controlling an arc furnace electrode in relation to a body of furnace charge, comprising a hydraulic motor, a reservoir of hydraulic fluid, electroresponsive pump means having an output connected to said hydraulic motor and an input coupled to said reservoir, conduit means coupling said hydraulic motor to said reservoir, normally closed electroresponsive valve means in said conduit means for preventing the discharge of said fluid from said motor to said reservoir, circuit means coupled to said electrode for producing a first output signal when the distance between said electrode and said charge becomes too small and for producing a second output signal when the distance between said electrode and said charge becomes too large, means coupled to said circuit means and operable upon the occurrence of said first signal to energize said electroresponsive pump means to drive said electrode upwardly and operable upon the occurrence of said second signal to energize said electroresponsive valve means so that said valve means is actuated to an open position to connect said fluid motor to said sump and allow said electrode to lower, said last mentioned means being operative to de-energize said pump means or said valve means upon the disappearance of said first and second signals respectively.

2. A control for an arc furnace electrode comprising a hydraulic motor, a reservoir of hydraulic fluid, electroresponsive pump means having an output connected to said hydraulic motor and an input coupled to said reservoir, conduit means coupling said hydraulic motor to said reservoir, normally closed electroresponsive valve means in said conduit means for preventing the discharge of said fluid from said motor to said reservoir, first circuit means coupled to said electrode for producing a first electrical signal which is a function of the current in said electrode and a second circuit means coupled to said electrode for producing a second electrical signal which is a function of the voltage across said electrode, means coupled to said first and second circuit means for energizing said electroresponsive pump means to drive said electrode upwardly when said first and second signals have one predetermined relation and for energizing said electroresponsive valve means so that said valve means is actuated to an open position to connect said fluid motor to said reservoir and allow said electrode to lower when said signals have another predetermined relation, said last mentioned means being operative to de-energize said pump means or said valve means when said signals have a relationship other than said one and another respectively.

3. Means for controlling an arc furnace electrode in relation to a body of furnace charge, comprising a fluid motor, a reservoir of hydraulic fluid, pump means including electroresponsive driving means and having an output connected to the pressure side of said fluid motor and an input coupled to said reservoir, conduit means coupling the pressure side of said fluid motor to said reservoir, normally closed valve means in said conduit means for preventing the discharge of said fluid from said motor, electroresponsive pilot means for actuating said valve means to an open position to connect said fluid motor to said sump and thereby initiate the lowering of said electrode, circuit means coupled to said electrode for producing a first electrical signal when the distance between said electrode and said charge is too short and a second electrical signal when the distance between said electrode and said charge is too long, signal responsive means connected to said circuit means and operative upon the occurrence of said first signal to complete an energizing circuit to said electroresponsive driving means to acuate said pump means and to drive said electrode upwardly, said signal responsive means also being operative upon the occurrence of said second signal to complete an energizing circuit to said pilot means to actuate said valve means so that said fluid motor is connected to said sump and said electrode is lowered, said signal responsive means being operative to interrupt said energizing circuits upon the respective disappearance of said signals.

4. A control for an arc furnace electrode comprising a hydraulic motor coupled to said electrode, a sump containing hydraulic fluid, pump means including electroresponsive driving means and having an output connected to the pressure side of said hydraulic motor and an input coupled to said sump, conduit means coupling the pressure side of said hydraulic motor to said sump, normally closed valve means in said conduit means for preventing the discharge of said fluid from said motor, electroresponsive pilot means for actuating said valve means to an open position, first circuit means coupled to said electrode for producing a first electrical signal which is a function of the current in said electrode and second circuit means coupled to said electrode for producing a second electrical signal which is a function of the voltage across said electrode, ratio means coupled to said first and second circuit means and operative when said first and second signals have one predetermined ratio to complete an energizing circuit to said electroresponsive driving means to actuate said pump means and drive said electrode upwardly, said ratio means also being operative when said signals have another predetermined ratio to complete an energizing circuit to said pilot means to open said valve means so that said fluid motor is connected to said sump and said electrode is lowered, said ratio means being operative to open said energizing circuits to said electroresponsive driving means and to said pilot means when said signals have ratios different than said one or another predetermined ratios respectively.

5. A control for an arc furnace electrode comprising a hydraulic motor coupled to said electrode, a sump containing hydraulic fluid, pump means including electroresponsive driving means and having an output connected to the pressure side of said hydraulic motor and an input coupled to said sump, conduit means coupling the pressure side of said hydraulic motor to said sump, normally closed valve means in said conduit means for preventing the discharge of said fluid from said motor, electroresponsive pilot means for actuating said valve means to an open position, first circuit means coupled to said electrode for producing a first voltage signal which is a function of the current in said electrode and second circuit means coupled to said electrode for producing a second voltage signal which is a function of the voltage across said electrode, force balance means including a first coil connected to said first circuit means and a second coil connected to said second circuit

means, said force balance means also including a balance beam deflectable when said first and second voltage signals have one predetermined ratio to complete an energizing circuit to said electroresponsive driving means to actuate said pump means and to drive said electrode upwardly, said beam also being deflectable when said voltage signals have another predetermined ratio to complete an energizing circuit to said pilot means to actuate said valve means so that said fluid motor is connected to said sump and said electrode is lowered.

6. A control for an arc furnace electrode comprising a hydraulic motor, a sump containing hydraulic fluid, pump means including two-speed electroresponsive driving means and having an output connected to the pressure side of said hydraulic motor and an input coupled to said sump, first and second conduit means in parallel relation for coupling the pressure side of said hydraulic motor to said sump, first and second normally closed valve means in said first and second conduit means respectively for preventing the discharge of said fluid from said motor, first and second electroresponsive pilot means for actuating said first and second valve means to open positions respectively, first circuit means coupled to said electrode for producing a first electrical signal which is a function of the current in said electrode and second circuit means coupled to said electrode for producing a second electrical signal with a function of the voltage across said electrode, force balance means coupled to said first and second circuit means and being operative when said first and second signals have one predetermined relation to complete an energizing circuit to said electroresponsive driving means to actuate said pump means to drive said electrode upwardly, said force balance means also being operative when said signals have another predetermined relation to complete an energizing circuit to said first pilot means to actuate said first valve means to an open position so that said fluid motor is connected to said sump and said electrode is lowered, and manually operable means for placing said second pilot means in parallel circuit relation with said first pilot means so that two parallel discharge paths are provided for a more rapid electrode lowering, said manually operable means also being operative to change the speed of said electroresponsive driving means for a more rapid electrode raising, said force balance means being operative to interrupt the energizing circuits to said driving means and said first pilot means when said signals have relationships other than said one or another respectively.

7. Means for controlling an arc furnace electrode in relation to a body of furnace charge, comprising a hydraulic motor, electroresponsive pump means having an output connected to said hydraulic motor, conduit means coupled to said hydraulic motor, normally closed valve means in said conduit means for preventing the discharge of hydraulic fluid from said motor, electroresponsive valve control means for opening said valve means, circuit means coupled to said electrode for producing a first electrical output signal when the distance between said electrode and said charge becomes too small and for producing a second electrical output signal when the distance between said electrode and said charge become too large, electrical signal responsive means coupled to said circuit means and to said pump means and to said valve control means, said signal responsive means being operative upon the

occurrence of said first signal to energize said electroresponsive pump means to drive said electrode upwardly and upon the occurrence of said second signal to energize said electroresponsive valve control means to open said valve means and allow the discharge of hydraulic fluid from said motor so that said electrode is lowered, said signal responsive means being operative to de-energize said pump means or said valve control means upon the disappearance of said first and second signals, respectively.

8. Means for controlling an arc furnace electrode in relation to a body of furnace charge, comprising a fluid motor, pump means including electroresponsive driving means and having an output connected to the pressure side of said fluid motor, conduit means coupled to the pressure side of said fluid motor, normally closed valve means in said conduit means for preventing discharge of fluid from said motor, electroresponsive pilot means for actuating said valve means to an open position to vent said fluid motor and thereby initiate the lowering of said electrode, circuit means coupled to said electrode and to said driving means and said pilot means, said circuit means being operative when the distance between said electrode and said charge is too short for energizing said driving means so that said electrode will be elevated, said circuit means also being operative for energizing said pilot means when the distance between said electrode and said charge is too long so that said valve means is opened and said electrode is lowered.

9. Means for controlling an arc furnace electrode in relation to a body of furnace charge, comprising a fluid motor, electroresponsive pump means having an output connected to the pressure side of fluid motor, conduit means coupled to the pressure side of said fluid motor, normally closed valve means and said conduit means for preventing discharge of hydraulic fluid from said motor, electroresponsive valve control means for actuating said valve means to an open position to vent said fluid motor and thereby initiate the lowering of said electrode, circuit means coupled to said electrode for producing a first electrical signal when the distance between said electrode and said charge is too short and a second electrical signal when the distance between said electrode and said charge is too long, signal responsive means connected to said circuit means and operative upon the occurrence of said first signal to complete an energizing circuit to said electroresponsive pump means to drive said electrode upwardly, said signal responsive means also being operative upon the occurrence of said second signal to complete an energizing circuit to said electroresponsive valve control means to actuate said valve means so that said fluid motor is vented and said electrode is lowered, said signal responsive means being operative to interrupt said energizing circuits upon the respective disappearance of said signals.
